CLAIM

The ornamental design for a splice connector for handrails, as shown and described.

DESCRIPTION

FIG. 1 is a front perspective view of a splice connector for handrails in accordance with the present invention;

FIG. 2 is a rear view thereof;

FIG. 3 is a front view thereof;

FIG. 4 right side view thereof, with the left side view being a mirror image;

FIG. 5 is an end view thereof;

FIG. 6 is perspective view illustrating placement of the splice connector in a handrail environment; and,

FIG. 7 is another perspective view thereof.

The broken lines depicting the handrail environment in FIGS. 6 & 7 form no part of the claimed design.
